[57] ABSTRACT

Electronic gating circuits are provided to yield closed current paths upon actuation of associated momentary contact switches. An erasing circuit is also energized upon actuation of a momentary contact switch to cause electronic gating circuits previously placed in the closed current path condition to be returned to an open circuit condition. Continued actuation of more than one momentary contact switch during operation of the erasing circuit will prevent the gating circuits associated with the actuated switches from being placed in an open circuit condition.

MULTIPLE CHOICE SELECTOR DEVICE

BACKGROUND OF THE INVENTION

1. Field of the Invention

This invention relates to a device for providing an operator with the means to make multiple choice selections to provide corresponding output signals in response to operator input choices, and for erasing previously selected output signals not presently selected. More particularly, this invention relates to a selector switch and interlock arrangement for selecting operator desired responses both individually and in groups from a multiplicity of operational electronic circuits, such as rhythm accompaniment circuits for an electronic organ.

2. Description of the Prior Art

Prior art multiple choice switching devices heretofore known to the art for use in electronic organs and related devices are mechanical switches which inherently have had several disadvantages. For example, one such prior art multiple choice switch heretofore utilized in conjunction with rhythm accompaniment devices for electronic organs has the undesirable feature of allowing the operator the choice of only one rhythm accompaniment at a time. The operator makes a rhythm accompaniment selection by pressing the appropriate button marked for that selection and the action of pressing the selector button releases any previously selected button. Thus, prior art devices have provided a simplified erasing feature which permits the operator to erase the previous selection by actuation of a new choice selection.

The mechanical configuration of another of the prior art switches does permit the operator to make more than one rhythm accompaniment selection provided the operator is capable of pressing the buttons exactly simultaneously so that the mechanical latching element of the switch will latch both buttons simultaneously. However, simultaneous selection is extremely difficult with this prior art device because of the close mechanical tolerances of the mechanical latching elements. Consequently, the organ operator often is required to make many numerous attempts to press the buttons simultaneously before a dual choice selection can be achieved. Often, regardless of how many attempts are made, the operator is unsuccessful in his attempts to make a dual choice selection with this prior art switch because he is unable to get both buttons to latch simultaneously. Further, three or more rhythm accompaniment choices are even more difficult since the operator is required to press the three or more buttons exactly simultaneously to achieve simultaneous latching of the buttons.

Moreover, with the prior art mechanical multiple choice switching devices, it is extremely difficult to retain that choice while making additional selections once a choice has been made since the erasing element of the switch releases all previously selected buttons upon the actuation of the new choice button. To retain the previously selected choice, it is necessary for the operator to attempt to hold the previously selected button in exactly the same position while pressing the new choice selection button so that simultaneous latching will occur. However, since the choice buttons are spring loaded it is extremely difficult for the operator to retain the button in exactly the same position after unlatching. Thus, retention of a previous selection while making an additional selection is very difficult in the prior art mechanical switches.

The present invention provides substantial improvements over the prior art mechanical multiple choice selector switches. The present invention allows the operator to make one or more rhythm accompaniment selections by pressing one or more buttons contemporaneously. With the present invention, it is not necessary for the operator to press the buttons exactly simultaneously. The operator can make one selection by pressing a button and as long as he holds down that button he can make as many additional choices as he wishes.

All previously selected rhythm accompaniments are erased in the present invention if the operator does not desire to retain them. Further, if the operator desires to retain a previously selected rhythm accompaniment, he may easily retain

that choice by pressing that selector button while he makes additional selections. Further, if the operator wishes to erase all previous selections so that no rhythm accompaniment is provided, a cancelling switch is provided to cancel all selections. Thus, the present invention provides substantial improvement over the prior art mechanical multiple choice switching devices.

SUMMARY OF THE INVENTION

10 A multiple choice selector device provides an operator with the opportunity to select one or more output signals for operating corresponding devices, to receive and respond to the output signals to provide operator desired responses. The

15 selector generally comprises a multiplicity of gating means, which act as memory means and erasing means in providing output signals to the individual responding devices upon individual choice excitation by an operator, in providing an erasing signal upon excitation by the operator, and in terminating existing output signals of those gating means for

20 which no co-existent external operator excitation is present by receipt of a transitional input signal. Additionally, there is provided a transitional input signal generating means for providing a transitional input signal in response to an erasing signal to terminate existing output signals of those gating means for which co-existent operator choice excitation is not provided. The duration of the transitional input signal is controlled by a limiting means to restrict the duration of the signal sufficiently to prevent release of a switch button before application of the erasing means.

25 Therefore, a primary object of the present invention is to provide a new and improved multiple choice selector device that permits the operator to easily and quickly make one or more contemporaneous selections.

30 Another object of the present invention is to provide a multiple choice selector device which permits previously selected choices to be easily retained while additional selections are made.

35 A further object of the present invention is to provide a new and improved multiple choice selector device which erases all previously selected choices no longer desired by the operator while allowing the operator to easily retain desired selections.

40 A further object of the present invention is to provide a relatively compact substantially maintenance free solid state electronic switching device for providing an operator the opportunity to easily make one or more multiple choice selections.

45 A further object of the present invention is to provide a new and improved multiple choice selector device which permits the operator to erase all previously selected choices without making a new choice and thereby eliminate all output signals.

BRIEF DESCRIPTION OF THE DRAWING

50 The FIG. 1 is a circuit diagram of a preferred embodiment of the present invention.

DETAILED DESCRIPTION OF THE INVENTION

55 With reference to the drawing, shown are two gating circuits 10 enclosed by rectangles of repeat lines. For space purposes, only two gating circuits are depicted in the drawing, however, it should be expressly understood that a multiplicity of gating circuits may be provided in parallel to gating circuits 10 to provide as many selections as desired.

60 Gating circuits 10 comprise complementary silicon controlled rectifiers 12 having anode terminals 14, cathode terminals 16 and gate terminals 18. Complementary silicon controlled rectifiers are normally conducting if the gate is at a lower potential than the anode. Conduction ceases if the current falls below a given level.

65 Connected from a bias voltage line 20 to the gate terminals 18 are bias resistors 22. Connected in parallel from the cathode terminals 16 to ground are load resistor 24 and indicating lights 26. Also connected to cathode terminals 16 are output jacks 28. The rhythm accompaniment devices (not

shown) may be connected to output jacks 28 to receive voltage produced across the parallel combination of load resistors 24 and indicating lights 26 when current is flowing. Connected from gate terminals 18 to common signal line 30 are normally open choice selector switches 32, which are of the type known as momentary contact switches.

Also connected from common signal line 30 to ground is an erasing voltage resistor 34. In parallel with erasing voltage resistor 34 to ground are foot switch terminals 36, which provide a means of disabling the erasing means while making multiple choices. A foot pedal switch arrangement (shown substantially at 35) may be connected across foot switch terminals 36 to facilitate operation.

Common signal line 30 is connected to the base 37 of a first NPN transistor 38. The emitter 39 of the first NPN transistor 38 is connected to ground, and the collector 41 of first NPN transistor 38 is connected to resistors 40 and 42. Resistor 40 is connected to bias voltage line 20, and resistor 42 is connected to the base 43 of second NPN transistor 44.

The emitter 45 of a second NPN transistor 44 is connected to ground and the collector 47 of second NPN transistor 44 is connected to resistor 46 and capacitor 48. Resistor 46 is connected to bias voltage line 20, and capacitor 48 is connected from the collector 47 of second NPN transistor 44 to resistor 50 and the anode 51 of diode 52. Resistor 50 is connected to ground and cathode 53 of diode 52 is connected to the base 55 of a third NPN transistor 54.

The emitter 57 of third NPN transistor 54 is connected to ground and the collector 59 of third NPN transistor 54 is connected to terminal 56. Connected from terminal 56 to ground is cancelling switch 58. Also connected to terminal 56 is the base 61 of fourth NPN transistor 60. Also connected from terminal 56 to ground is the parallel combination of capacitor 62 and zener diode 64. The zener diode fixes the potential at terminal 56 at the breakdown voltage of the zener.

Connected from the collector 67 of fourth NPN transistor 60 to terminal 56 is a resistor 66. Collector 67 of fourth NPN transistor 60 is also connected to bias voltage line 20, and emitter 69 of fourth NPN transistor 60 is connected to main current line 68. Main current line 68 is connected to anode terminals 14 of the controlled rectifiers 12. Also connected between main current line 68 and ground is capacitor 70.

Voltage is provided on bias voltage line 20 through resistor 72 by an electrical power source 74 (graphically represented by a battery symbol.) Also connected between bias voltage line 20 and ground is surge eliminating capacitor 76.

Control rectifiers 12 have the advantageous physical characteristics of shifting from a non-conducting state to a conducting state as a result of the reduction of voltage below a determinable level (gating voltage) applied at gate terminal 18. Once shifted from a non-conducting state to a conducting state, control rectifiers 12 continue to remain in a conducting state after the gate terminal voltage returns to the original level. The control rectifiers 12 can be shifted from a conducting to a non-conducting state when the anode 14 to cathode 16 input current falls below a determinable level. However if the voltage applied at the gate terminal 18 is below the gating voltage level necessary to shift the control rectifier 12 to a conducting state reduction of the anode 14 to cathode 16 current will not shift the control rectifier 12 back to a non-conducting state.

Gate terminals 18 are normally biased to hold control rectifiers 12 in a non-conducting state. When choice selector switches 32 are open, the voltage of gate terminals 18 is the same as the voltage of bias voltage line 20, since no current is flowing through bias resistors 22. When one or more choice selector switches 32 are closed, current flows from bias voltage line 20 through bias resistor 22, choice selector switch 32 and erasing voltage resistor 34 to ground. Because of the current flow through bias resistor 22, the voltage at gate terminal 18 is reduced below the voltage of bias voltage line 20 by the voltage drop across bias resistor 22. By proper selection of the value of bias resistor 22, this voltage drop may be established

at a level sufficient to shift control rectifier 12 from a non-conducting state to a conducting state. Current then flows from power source 74, through resistor 72, through bias voltage line 20, through normally conducting fourth NPN transistor 60, through main current line 68, through the conducting controlled rectifier 12 and through the parallel combination of load resistor 24 and indicating light 26 to ground. The flow of current through the parallel combination of load resistor 24 and indicating light 26 causes indicating light 26 to illuminate and also produces an output voltage. This output voltage can be picked up at output jack 28 and utilized to actuate a corresponding rhythm accompaniment circuit (not shown).

Upon closing of one or more choice selector switches 32, an input voltage is applied to base 37 of first NPN transistor 38 equal to the current in amperes flowing through erasing voltage resistor 34 times the resistance in ohms of erasing voltage resistor 34. This erasing voltage is amplified by first NPN transistor 38 and the amplified signal from the collector 41 of first NPN transistor 38 is applied across resistor 42 to the base 43 of second NPN transistor 44. This erasing signal is in turn amplified by second NPN transistor 44 and a transitional surge of current is conducted across capacitor 48 until capacitor 48 becomes fully charged. Once charged, capacitor 48 blocks all further direct current and this limits the duration of the erasing signal. This transitional surge of current across capacitor 48 creates a transitional voltage signal across resistor 50 to ground, and this transitional voltage signal is applied to base 55 of third NPN transistor 54 through diode 51. Capacitor 48 and resistor 50 form a differentiator circuit.

Because of the biasing of third NPN transistor 55, the transitional voltage signal applied to base 55 causes third NPN transistor 54 to momentarily saturate and thus momentarily shift from a non-conducting condition to a fully conducting condition effectively grounding terminal 56. The effective grounding of terminal 56 also grounds base 61 of fourth NPN transistor 60, which momentarily shifts fourth NPN transistor 60 from a highly conducting state to a relatively low conducting state. Thus, the flow of current through main current line 68 to anodes 14 of control rectifiers 12 is momentarily reduced. Fourth NPN transistor 60 is biased to shift to a current level below that necessary to sustain control rectifiers 12 in a conducting condition upon grounding of base 61. Thus, the closing of choice selector switches 32 generates a signal that is amplified to momentarily ground base 61 of fourth NPN transistor 60 and thereby momentarily reduce the current in main current line 68 and erase the flow of current in the non-selected gating circuits 10.

Diode 52 is provided to prevent a double surge of current to base 55 of third NPN transistor 54 upon the collapse of the current surge across capacitor 48. Capacitors 62, 70 and 76 are provided to eliminate AC surges in the circuit and thereby provide a more stable direct current voltage and eliminate the possibility of accidental choice erasing by unwanted AC voltage fluctuations.

It should be expressly understood that the reduction of current level in main current line 68 is a momentary reduction in current resulting from the momentary saturation of third NPN transistor 59 caused by the voltage surge applied to base 55 across resistor 50. Once capacitor 48 is fully charged, no further direct current will flow across capacitor 48 and through resistor 50. Thus, after initial closing, as long as a choice selector switch 32 remains closed, no additional surges will be generated across capacitor 48 since a constant direct current voltage is being applied across erasing voltage resistor 34 and amplified by transistors 38 and 44. Consequently, once one choice selector switch 32 is closed and remains closed, additional selection may be made individually without generating an erasing signal since unfluctuating direct current continues to be applied across erasing voltage resistor 34. Without a fluctuation in this current, no additional current surges will be transmitted across capacitor 48 and thus no erasing current drop will result in main current line 68. Thus, the reduction of current in main current line 68 in response to the closing of a

choice selector switch 32 does not operate to shift a particular control rectifier 12 from a conducting to a non-conducting state if the corresponding choice selector switch 32 is closed at the time the current in main current line 68 is reduced.

Once all choice selector switches 32 have been opened and current stops flowing through erasing voltage resistor 34, any subsequent closing of a choice selector switch 32 produces a current surge across erasing voltage resistor 34 which is amplified to saturate third NPN transistor 54, ground base 61 of fourth NPN transistor 60 and reduce current in main current line 68 below the level necessary to erase the previously conducting control rectifiers 12 for which corresponding choice selector switches 32 are not closed.

An additional feature provided by this embodiment is cancelling switch 58. If the operator wishes to terminate all rhythm accompaniments, cancelling switch 58 may be closed. This grounds base 61 to fourth NPN transistor 60 thereby reducing the current in main current line 68 and shifting all conducting control rectifiers 12 to a non-conducting state.

I claim:

1. A selector switch and interlock arrangement comprising: a plurality of momentary contact switches, each of said momentary contact switches adapted to initiate a sustained function;

memory means responsive to actuation of a momentary contact switch to record that said one momentary contact switch has been actuated and thereby sustain the continuing function after de-actuation of said one momentary contact switch;

erasing means responsive to actuation of a momentary contact switch to erase any record in said memory means of any prior actuations of a momentary contact switch; and limiting means rendering said erasing means ineffective with respect to momentary contact switch actuations that are coextensive for any period of time.

2. An arrangement as claimed in claim 1 wherein said memory means comprises a plurality of electronic gating devices.

3. An arrangement as claimed in claim 2 wherein: said electronic gating devices are complementary silicon controlled rectifiers having anode, cathode and gate electrodes; and

each of said momentary contact switches is connected to 45 the gate electrode of an associated complementary silicon controlled rectifier to trigger conduction thereof upon closure of the associated switch.

4. An arrangement as claimed in claim 3 wherein said erasing means comprises:

a power transistor conveying current to each of said complementary silicon controlled rectifiers; and control means responsive to closure of a momentary contact switch to reduce conduction of said power transistor.

5. An arrangement as claimed in claim 4 wherein said limiting means comprises a differentiator adapted to limit reduction of conduction by said power transistor to a very short period of time.

6. An arrangement as claimed in claim 1 wherein said erasing means may be rendered ineffective by a controlling pedal switch.

7. A selector switch and interlock arrangement comprising: a plurality of momentary contact switches, each of said switches adapted to initiate a sustained function; 65 an electronic gate connected to each momentary contact switch, said gate being placed in a conducting state upon closure of its associated momentary contact switch and adapted to remain in the conducting state until the current passing therethrough is decreased below a given level;

a power transistor supplying current to said electronic gates; an erase control means adapted to decrease conduction of said power transistor in response to closure of a momentary contact switch; and

a limiting differentiator adapted to limit the decrease in conduction of said power transistor to a period of time long enough to cause any gates in a conducting state to be transferred to a non-conducting state and short enough to prevent release of the momentary contact switch while said power transistor is in a reduced conducting state.

8. A device for providing multiple choice output signals to a means for receiving, interpreting and responding to the signals in response to an operator's choice comprising:

a multiplicity of gating means, each of said gating means for individually providing a concurrent sustainable output signal in response to momentary co-existent individual external operator excitation, for providing an erasing signal in response to initiation of external operator excitation, and for terminating any existing output signals in response to an input transitional signal of those gating means for which no co-existent corresponding external operator excitation is present; and

an input transitional signal means for providing an input transitional signal to said multiplicity of gating means in response to the erasing signal to deactivate said multiplicity of gating means;

whereby more than one output signal may be selected by co-existent operator excitation of the corresponding gating means and all existing output signals of non-excited gating means are thereby terminated.

9. A multiple choice selector device for providing operator desired output current signals in response to the operator choice comprising:

a multiplicity of electrical current gating means for individually shifting from a non-conducting state to a conducting state upon individual external excitation to provide a corresponding output current, for providing an erasing current upon external excitation; and for individually shifting back to a non-conducting state upon reduction of input current below a determinable level, when no corresponding external excitation is present;

a pulse amplifying means for amplifying the erasing current and providing an output current pulse in response to the erasing current; and

a normally conducting power switch means for providing input current to said gating means and for reducing the input current below the level necessary to shift said gating means from a conducting to non-conducting state in response to the input of a current pulse from said amplifying means,

whereby, one or more output currents may achieve by external excitation of the corresponding gating means and all previously conducting non-externally excited gating means may be shifted to a non-conducting state.

10. A multiple choice selector device for providing operator desired output voltage signals to means for receiving and responding to the output voltage signals comprising:

an electrical power source;

a multiplicity of gate controlled rectifying means, each having an anode, a cathode and a gate terminal and shiftable from a non-conducting state to a conducting state upon reduction of the gate terminal voltage below a predetermined level and remaining in a conducting state until the anode to cathode current is reduced below a predetermined level when the gate terminal voltage is above the level necessary to shift the gate rectifying means to a conducting state, said gate terminal normally biased by the power source to hold said controlled rectifier in a non-conducting state;

a multiplicity of load resistor means individually in series from ground to the cathode of the controlled rectifying means for providing output voltage signals when said controlled rectifying means are in a conducting state;

a multiplicity of normally open triggering switch means individually connected at one side with the gate terminals for reducing the gate terminal voltage and placing the rectifier means in a conducting state when closed;

- a first resistor means commonly connected from the opposite side of the triggering switch means to ground for providing an erasing voltage upon closing of a triggering switch means;
- a pulse amplifying means for amplifying the erasing voltage and providing an output pulse of electrical current;
- a normally conducting power switch means having an input, output and control terminal for providing current from said power source to the anodes and for reducing the current below the level necessary to shift said controlled rectifiers to a non-conducting state when the control terminal is grounded;
- a grounding switch means controlled by the output pulse from said pulse amplifying means for grounding the control terminal of power switch means in response to a pulse provided by said pulse amplifying means;

whereby, one or more output voltage signals may be achieved across the load resistor means by closing of one or more corresponding triggering switch means thereby shifting the corresponding control rectifying means to a conducting state and whereby all previously conducting control rectifying means for which corresponding triggering switch means are not closed are shifted to a non-conducting state by the grounding of the control terminal of the power switch means.

- 10 11. A multiple choice selector device as claimed in claim 10 and further comprising:
- a cancelling switch means for grounding the control terminal of said power switch means when closed to shift all conducting gate controlled rectifying means from a conducting state to a non-conducting state.
